UNITED STATES PATENT OFFICE.

JACOB KURTZ, OF DARRAGH, AND THEODORE HOCHRITER, OF GREENSBURG,
PENNSYLVANIA.

COAL-MINING MACHINE.

957,510.

Specification of Letters Patent. Patented May 10, 1910.

Application filed October 9, 1908. Serial No. 456,899.

To all whom it may concern:

Be it known that we, JACOB KURTZ and THEODORE HOCHRITER, citizens of the United States, residing, respectively, at Darragh and Greensburg, in the county of Westmoreland and State of Pennsylvania, have invented a new and useful Improvement in Coal-Mining Machines, of which the following is a specification.

10 This invention relates to rotatable and swinging cutters carried by a movable carriage, transported in turn by a truck movable on a track or on the floor of a mine tunnel or chamber.

15 The object of the invention is a device of this kind in which the cutters are advanced into the vein of coal by a rotary, boring movement, and also moved in an arc, thus cutting laterally after penetrating the 20 desired depth, the boring and swinging movements being under independent control of the operator.

25 A further object of the invention is to provide for vertical adjustment of the cutters, so that they can cut close to the floor of the mine, or can be elevated to pass over 30 obstructions.

The invention consists in the novel features of construction hereinafter described, 35 pointed out in the claims and shown in the accompanying drawings, in which—

Figure 1 is a plan view, a movable carriage being in section. Fig. 2 is a side view partly broken away. Fig. 3 is a vertical longitudinal section on the line 3—3 of Fig. 1. Fig. 4 is a central transverse section on the line 4—4 of Fig. 1. Fig. 5 is a plan view of the carriage. Fig. 6 is a horizontal section through the cutting mechanism on the line 6—6 of Fig. 4. Fig. 7 is a vertical section, enlarged, showing one-half of an end of the machine. Figs. 8 and 9 are detail sections of a truck wheel. Fig. 10 is a side elevation of a key for use with the 45 truck wheels. Fig. 11 is a detail section through the carriage. Fig. 12 is a detail vertical section through one of the supporting wheels showing the construction of the supports. Fig. 13 is a plan view showing 50 the cutters in a cutting position. Fig. 14 is a detail plan view of the cutting blades carried by a spiral flange. Fig. 15 is a detail side view of a portion of said flange and cutters. Fig. 16 is a perspective view of a 55 cutter retaining block. Fig. 17 is a perspective

view of the cutter. Fig. 18 is a perspective view of a retaining block co-operating with the block shown in Fig. 16. Fig. 19 is a vertical section through a casting detached from the machine.

In these drawings 1 represents a frame, mounted on wheels 2. The upper side members of the frame 1 form a track on which slides a carriage 3. The frame 1 has its ends braced by end plates 4. The frame 1 forms a track, the wheels 2, four in number, being provided with tread portions and flanges for traveling on a mine track. The wheels are provided with spurs 2^a which work through the tread for use when the truck is run on the floor of the mine. To throw these spurs in and out the following mechanism is provided for each wheel 2. Within each wheel is placed a cam wheel 6 having as many peripheral cam portions as there are spurs. The wheels are slotted as shown at 7 and perforations 8 are formed in the cams 6 to register with the slots 7. By engaging the opening 8 with a suitable implement, such as is shown at 6^a in Fig. 10, the cams can be turned. Springs 9 draw the spurs inwardly when the cam portions are shifted from beneath the spurs, and the spurs are forced outwardly again when the cams 6 are brought back to the position shown in Fig. 8. The truck wheels are mounted on stub shafts 10, and worm gears 11 are formed on all the wheel hubs. A sleeve 12 terminates in a bifurcated bracket which incloses the worm gear 11 on one side, each wheel being provided with one of these sleeves. The shafts 10 are journaled in the brackets of the sleeves 12 and it will be obvious that rotation of the sleeves and of the bracket will turn the wheels. In this manner the device is steered or guided when running on the mine floor. To effect this turning movement of the sleeve and to rotate the wheels 2 to give a forward or rearward movement to the truck the following mechanism is employed: A shaft 13 provided with a worm runs through and is keyed in the sleeve 12, the worm of the shaft meshing with the worm gear 11 of the wheel hub. Triangular shaped castings 14 are fitted into the corners of the frame 1 and are provided each with a longitudinal bore 14^a, the lower portion of which is of greater diameter than the upper. The sleeve 12 fits in the larger lower portion, while the worm

shaft 13 extends upwardly through the casting 14. A worm gear 15 is fixed on the sleeve 12 and meshes with a worm shaft 16, on the outer end of which is a hand wheel 16* so that the sleeve 12 can be rotated thus steering the device when run off the tracks.

At the upper ends of the shafts 13 are beveled gears 17, these gears occupying the four corners of the frame 1. Transversely mounted in the frame and adjacent its ends are shafts 18 which at their ends carry beveled gears 19. These shafts each carry a worm gear 20 meshing with worms 21 carried by a longitudinally extending shaft 22. The shaft 22 is geared for two speeds and for rotation in opposite directions by means of small, slideable high speed gears 23 and larger slideable low speed gears 24, said gears being shifted by a series of shifting levers 25.

The carriage 3 carries shafts 26 rotating in opposite directions and carrying large gears 27 meshing respectively with the high speed gears 23 and gears 28 meshing with the low speed gears 24. When the frame 1 is to remain stationary, both sets of gears are disengaged and the machinery hereafter described may be operated without driving the shaft 22. It will be understood that the gears 27 and 28 are carried by, but below the top of, the carriage 3.

To drive the shafts 26, beveled gears 29 on the adjacent sides of the gears 28 mesh with a beveled pinion 30 carried by a depending shaft 31. At its upper end this shaft carries a loose gear 32 and a friction ring or clutch 32* operated by a pivoted hand lever 33.

A motor 34 is mounted on the carriage, and the motor may be of any type, and the motor shaft carries a bevel pinion 35 which meshes with a beveled gear 36. A small gear wheel 37 fixed to or integral with the beveled gear 36 meshes with the loose gear 32 and also with a gear wheel 38 loosely mounted on a central shaft 39 and locked to said shaft by a friction clutch 39* similar to the clutch 32* and operable by a pivoted lever 40. It will now be obvious that by having gears 32 and 38 loose on their shafts and locking them by clutches either shaft may be driven independent of the other or both may be operated at the same time. The shaft 31 will hereafter be termed the drive shaft and the shaft 39 the cutter shaft.

Before describing the cutting mechanism, the description of those parts connected with the frame 1 will be completed. Journalized in the ends of said frame and adjacent its sides are worm shafts 41 which work in threaded boxes 42 carried by the carriage. A transverse shaft 43 carries at its ends beveled gears 44 which mesh with keyed gears 45 carried by the worm shaft 41. Shaft 43 is driven by means of a beveled gear 46

fixed on it and meshing with a beveled gear 47 carried by a shaft 48 on which is keyed a gear wheel 49 adapted to mesh with either of the gear wheels 29.

The cutter shaft 39 is a keyed shaft having vertical movement, and its lower depending portion is held loosely in a sleeve 50. Slidably held upon this sleeve is an angled casting 51 the lower horizontal portion of which extends laterally as shown at 52, and at its outer end carries oppositely extending hollow arms 53, also angled, and the end portions of these arms form bearings for cutters 54. In order to rotate these cutters the shaft 39 is provided with a bevel gear 55 which meshes with a similar gear 57 carried by a shaft 56 journaled in the horizontal portion 52. This shaft also carries a bevel gear 58 and in the arms 53 is journaled a shaft 59 provided with a bevel gear 60 which meshes with the gear 58 and which in turn carries bevel gears 61 meshing with bevel gears 63 carried by shafts 62 which extend into the cutters 54 and are secured to said cutters by any suitable means. These cutters 54 are provided with spiral ribs 64 and along said ribs are fixed a large number of cutting blades 65, the shanks of which are held in place upon the ribs 64 by means of suitable blocks 66 and 66*, which blocks are fastened by means of rivets and bolts to the ribs and cooperate in holding a cutting blade between each pair of blocks, as shown in Figs. 14 and 18 inclusive.

The vertical portion of the casting 51 has secured upon it a large gear wheel 67 and it will be obvious that by rotation of said gear wheel the casting will be rotated upon the sleeve 50 and the cutters will thus be swung in an arc. To drive the wheel 67 we provide at the four corners of the carriage 3 toothed drums 68, said drums being mounted vertically. These drums are of a sufficient length to allow for vertical movement of the casting 51 and accompanying movement of the wheel 67. Formed integral with the upper portion of each drum is a worm gear 69. Parallel shafts 71 are journaled in the carriage 3 and are provided with worm portions 70 which portions mesh respectively with the worm gear 69. Upon these shafts 71 are fixed bevel gears 72 which mesh with similar gears 73 carried at the ends of a shaft 74 upon which is fixed a bevel gear 75 meshing with a suitable gear carried by a shaft 76 which carries a small gear wheel 77 which meshes with either of the gear wheels 27, the gear 77 being slideable on the shaft 76 through means of a suitable lever 78.

By means of the above construction the cutters are rotated and are also capable of being swung in an arc and operated from either side of the machine, or from either end, as shown in Fig. 13. This swinging movement of the cutters may be employed

in cutting out an initial opening, making the cut practically square with the end of a mine tunnel so as to leave very little waste. After making such semi-circular cut and 5 cutting square to the end of the tunnel the gear wheel 77 may be disengaged and upon reversal of the travel of the carriage the cutters will cut back upon a straight line, such line being shown by the dotted line in 10 Fig. 13. Both cutters operate at the same time so that the direction of cutting can be changed at will without the operator stopping to manipulate any clutch or other device for throwing one cutter in and the other out of 15 the cutter-driving mechanism.

It is often advisable to tilt one side or other of the machine in order to incline the cutters slightly out of a horizontal plane. To effect this tilting movement we place at 20 each corner of the frame 1 a jack which consists of an angled casting 79 the lower portion of which rests upon the bracket of the sleeve 12 and the upper portion of which carries a threaded box 80 through which 25 works a jack screw 81 which screw is held in brackets 82 carried by the corner portions of the frame 1. By turning this screw by means of a wrench either the side of the machine, or one particular corner, or end may 30 be elevated, the inclination given to the cutters by such elevation depending partly upon the position into which the cutters are swung with relation to the tipped portion of the frame. A slidable bar 83 is also carried by the carriage 3, projecting beyond 35 each end of the carriage, and in position to strike the ends of the frame 1. This bar is connected to a shifting lever 84 which is a reverse lever which shifts the gear wheel 40 49 previously described. By means of this construction the carriage is automatically reversed as it approaches each end of the frame 1, by the bar 83 striking the frame end, or if it is desired to reverse the carriage before the carriage reaches the end of the frame said reversal can be effected by 45 means of the lever 84.

In order to adjust the cutters a lever 50 85 is pivoted at one end beneath the top of the carriage 3, and extends transversely across the carriage and at its free end is operated by a threaded rod 86, provided at its upper end with a hand wheel 87, which wheel is above the carriage top. The lever 55 85 engages in any suitable manner the casting 51 and vertical adjustment of said lever adjusts said casting. In order that the device may be run freely along a mine track to the place of use without operating any of

the machinery the track wheel 2 is connected 60 with the worm gear 11 by means of removable pins 88. By removing said pins the device may be run from place to place with all of the machinery described inoperative. To prevent the sides of the frame 1 from 65 scraping against sides of the mine tunnel we employ small side buffer wheels 89.

What we claim is:—

1. In a coal cutting machine, a horizontally movable carriage, a vertically adjustable 70 forked sleeve traveling with said carriage, spirally flanged shafts carried by the fork of the sleeve and extending laterally from the carriage, means for rotating said shafts, cutting blades held upon the flanges of the 75 shafts, and means for swinging said sleeve in a horizontal plane.

2. The combination with a wheeled frame, of a carriage movable thereon, means for moving said carriage upon the frame, a 80 sleeve depending from the under side of said carriage, an angled sleeve having a vertical portion slidably mounted upon the first mentioned sleeve and having a horizontal portion forked, a gear wheel fixed 85 upon the vertical portion of said second mentioned sleeve, vertically arranged toothed drums meshing with said gear wheel, rotatable shafts carried by the fork of the second mentioned sleeve, cutters carried by said shafts, means carried by said sleeve for rotating the said shafts, and means for sliding the second mentioned sleeve upon the first mentioned sleeve, the gear wheel being adapted to slide upon said 90 95 toothed drums.

3. A device of the kind described comprising a sliding carriage, a motor mounted upon said carriage, a slidable vertically arranged shaft, a friction clutch adapted to 100 lock said shaft to said motor, an angled vertically adjustable sleeve, the said sleeve having a forked horizontal portion, cutters carried by the sleeve fork, means for transmitting rotation of the slidable shaft to said 105 cutters, said means being carried by the sleeves and fork, a gear wheel fixed to and adjustable with said sleeve, and rotatable toothed drums meshing with said gear wheel, the said gear wheel being adapted to 110 slide vertically upon said drums during adjustment of the sleeve.

JACOB KURTZ.
THEODORE HOCHRITER.
